(No Model.)

W. J. KELLY.
RAILWAY SWITCH.

No. 405,361.

Patented June 18, 1889.

UNITED STATES PATENT OFFICE.

WILLIAM J. KELLY, OF BOSTON, ASSIGNOR OF ONE-HALF TO CHARLES H. ARNOLD, OF WOBURN, MASSACHUSETTS.

RAILWAY-SWITCH.

SPECIFICATION forming part of Letters Patent No. 405,361, dated June 18, 1889.

Application filed November 3, 1888. Serial No. 289,867. (No model.)

To all whom it may concern:

Be it known that I, WILLIAM J. KELLY, a citizen of the United States, and a resident of Boston, in the county of Suffolk and State of Massachusetts, have invented new and useful Improvements in Railway-Switches, of which the following, taken in connection with the accompanying drawings, is a specification.

This invention relates to improvements in railway-switches for the purpose of guiding cars from a single track to one of two branches, or vice versa, without the use of the ordinary movable point or tongue—in fact, without any movable part of the track or switch whatsoever.

This my invention I term a "diverter," and it is constructed as follows, reference being had to the accompanying drawings, wherein—

Figure 1 represents a plan view of the diverter and rails connected to its ends. Figs. 2, 3, 4, and 5 represent, respectively, enlarged cross-sections on the lines A A, B B, C C, and D D shown in Fig. 1.

Similar letters refer to similar parts whenever they occur on the different parts of the drawings.

E, F, and G represent rails of the usual form adapted for horse-car traffic, said rails having, respectively, the wheel-bearings e f g, wheel-flange grooves e' f' g', and continuous side wheel-guard lips e'' f'' g'', as is common in rails of this kind.

H is the diverter, having in one end, where it is connected to the single rail E, a wheel-bearing h, a wheel-flange groove h', and continuous side wheel-guard lip h'', of a size and shape equal with and corresponding to the respective parts e e' e'' on said rail E.

The wheel-bearing h of the diverter is curved, as shown, and forms a continuation of the wheel-bearings e and g on the respective rails E and G, as shown in Fig. 1. The lip h'' of the diverter is also curved and forms a continuation of the lips e'' and f'' on the respective rails E and F, as shown in Fig. 1. The opposite ends of the diverter are secured in a suitable manner to the abutting ends of the rails E, F, and G; but I wish to state that I do not confine myself to any particular device for securing said parts together, as this may

be done by means of bolts, screws, spikes, or other well-known devices without departing from the essence of my invention.

h³ and h⁴ are wheel-flange grooves in the forked end of the diverter, which grooves form in one end continuations, respectively, of the grooves f' g' in the rails F and G and converge toward and run into the groove h', that forms a continuation of the groove e' in the rail E, as shown in Fig. 1.

Between the diverter-grooves h³ and h⁴ is arranged the stationary tongue or pointed wheel-bearing h⁵, which is cast or made in one single piece with the diverter H, as shown in Figs. 1 and 4, and has its pointed end located centrally in the single wheel-flange groove h'. At the end of the diverter that connects with the rails F and G the end of the tongue h⁵ is enlarged, so as to form a continuous flush edge with the wheel-tread f of the rail F and with the guard-lip g'' of the rail G. This construction enables me to dispense with the use of the point h⁵ on one of the rails, as the use of one will accomplish the result equally as well, for the reason that whichever groove the wheel enters it will have a continuous flange-bearing surface from the moment it passes the point of the tongue h⁵, either against the guard-lip h³, if entering the rail F, or against the tongue h⁵, if entering the rail G.

The diverter-grooves h³ and h⁴ are both curved, the radii of the groove h⁴ being longer than the radii of the groove h³ on the right-hand rail-diverter, as shown in Fig. 1, and similarly on the left-hand rail, it being essential that the diverter-grooves shall have different radii—one greater than the other—to enable the car when going in the direction of the arrow shown in Fig. 1 to be properly guided to the right, or eventually straightforward, as may be required.

In practice it is always desirable to locate the diverter upon that side of the track to which the car is to be guided from a straight line. When the diverter is to be used for the purpose of guiding a car from a straight line toward the right, I make it curved toward the right, as shown in Fig. 1, and vice versa if the diverter is desired for the purpose of guiding a car from a straight line toward the left.

When the car is driven in the direction shown by arrow in Fig. 1, if it is desired to run onto the rail G, all that is necessary to do is to guide the horses toward the right, causing the wheels to run on the diverter wheel-bearing h and onto the wheel-bearing g of the said rail G.

If it is desired to run onto the rail F, it is only necessary for the driver on approaching the diverter to guide the horses toward the left, causing the car-wheel flange to be guided into the diverter-groove h^3 , and causing the wheels to run on the tongue h^5 , and thereby to be guided onto the wheel-bearing f of the rail F.

15 The object of having one of the grooves in the diverter sharper than the other is to permit the wheels of the car to be properly and easily guided in the desired direction without the use of a movable tongue or switch-point.

20 When driving in a direction opposite to that shown by arrow in Fig. 1 from either of the rails F or G, the wheels will be automatically guided onto the rail E without any care on the part of the driver.

25 What I wish to secure by Letters Patent, and claim, is—

1. In a railroad - switch, the combination, with the main rail E and the branching rails F and G, of a diverter interposed between said main and branch rails and consisting of a continuous wheel-bearing to one branch rail, a continuous side guard-lip to the other branch rail, and a central fixed pointed tongue running back and forming a continuous flush edge for the wheel-tread of one rail and for 35 the side guard-lip of the other rail, substantially as described.

2. A railroad-switch consisting of a wheel-tread, side guard-lip, and central pointed tongue broadened at one end and serving as 40 wheel-tread and side guard-lip, all cast in one integral piece and adapted to be interposed between a main rail and two branch rails, substantially as described.

In testimony whereof I have signed my name 45 to this specification, in the presence of two subscribing witnesses, on this 30th day of October, A. D. 1888.

WILLIAM J. KELLY.
